[57] CLAIM

The ornamental design for a stand for potted plants, as shown.

DESCRIPTION

FIG. 1 is a front elevation view of a stand for potted plants showing my new design.

FIG. 2 is a top plan view thereof.

FIG. 3 is a side elevational view taken from the left of FIG. 1.

FIG. 4 is a bottom plan view thereof.

FIG. 5 is a rear elevational view thereof.

FIG. 6 is a side elevational view taken from the right of FIG. 1.
